UNITED STATES PATENT OFFICE.

HARRY D. NEFF, OF CAMBRIDGE, MASSACHUSETTS, ASSIGNOR TO RE-FILIT BROOM COMPANY, OF BOSTON, MASSACHUSETTS, A CORPORATION OF MASSACHUSETTS.

BROOM-BUNDLE-MAKING MACHINE.

1,421,812.

Specification of Letters Patent.

Patented July 4, 1922.

Application filed November 12, 1920. Serial No. 423,730.

To all whom it may concern:

Be it known that I, HARRY D. NEFF, a citizen of the United States, and resident of Cambridge, in the county of Middlesex 5 and State of Massachusetts, have invented an Improvement in Broom-Bundle-Making Machines, of which the following description, in connection with the accompanying drawings, is a specification, like letters on 10 the drawings representing like parts.

My present invention relates to brooms, and more particularly to machines for making bundles for use in section brooms.

As is well known, the ordinary form of 15 broom is unsatisfactory and uneconomical, as it is practically useless before the broom fibres are worn out. This is because the bundles of broom fibres wear principally at the corners, and a considerable number 20 of fibres in the middle portion of the bundle are still usable when the broom is unserviceable because of the excessive wear on the corners.

With a view to obviating the objectional features noted above, I have devised 25 an improved form of broom, consisting broadly in a hollow receiving head into which may be placed a plurality of small bundles. Such a construction is described 30 and claimed in my copending application Ser. No. 373,595, filed April 13, 1920, Patent 1,350,514, dated August 24, 1920, and Patent 1,367,753, dated Feb. 8, 1921. The arrangement of the bundles in such head 35 may be changed at will, so that the fibres of the various bundles will receive equal wear, or the worn corner bundles may be replaced by new bundles.

In my development of the broom industry, 40 as above outlined, I have found it necessary to devise efficient and economical means to manufacture such bundles, and I have found the best bundle to be one in which the fibres are securely fastened at one end by a metal strap or ring, such ring 45 when in operative position being oval shaped to more securely grip the broom fibres and to fit into the broom head.

To accomplish these results in a satisfactory manner, I have devised the present invention for rapidly and economically tightening the metal ring to the broom fibre 50 bundles.

The principal object of my present invention, therefore, is an improved machine for

positioning and securing binding rings on a bundle of broom fibres.

Other objects and novel features of construction and arrangement of parts constituting my improved machine will appear 60 as the description of the invention progresses.

In the accompanying drawings illustrating the preferred embodiment of my invention,

Fig. 1 is a front elevation, partly in section;

Fig. 2 is a sectional side elevation, on the line 2—2 of Fig. 1;

Fig. 3 is a plan view;

Fig. 4 is a detail of one of the half dies; and

Fig. 5 is a detail of one of the broom units, showing the metal band in position and before being firmly secured to the unit. 75

Referring to the drawings, 10 designates a base having formed integral therewith uprights 11 and 12 in which are formed bearings 13, 13 and 14, 14, as shown.

A lower pair of these bearings 13 and 14 80 are in horizontal alinement with each other and have rotatably mounted therein a shaft 15, while the upper pair of bearings 13 and 14 are also in horizontal alinement with each other and directly over the lower pair, 85 and have rotatably mounted therein a shaft 16. Adjacent the bearings 13 and 14 rigidly attached to the shafts 15 and 16 respectively, are circular members 17 and 26 respectively.

The member 17 is provided with gear 90 teeth 18 at one edge, while the remainder of the face of such member is provided with a plurality of circumferential grooves 19, such remainder of the face of such member being provided with a plurality of recesses 95 20, conveniently spaced about the periphery of the member and in which are clamped half dies 21. The contour of these half dies is such that they flare downwardly at 22 while the remainder 23 is horizontal, this 100 contour being necessary in order to impart the proper shape to the material worked upon. They are held in position in the recesses 20 by screws 24, or in any other suitable manner. The other member 26 is of 105 less diameter than the diameter of the member 17, and is provided with gear teeth 25 which mesh with the gear teeth 18 on the said member 17 and thus act to rotate said member. This member 26 is also provided 110

with a plurality of grooves 27 which interlock with the grooves 19 in the member 17 and prevent side motion of said members relative to each other. Recesses 28, similar 5 in character to the recesses 20 in the member 17, are spaced about the periphery of the member 26, the spacing being such that the recesses 28 register with the recesses 20 as the said members rotate. Half dies 21 10 are secured in the recesses 28 by screws (not shown). The shaft 16 extends beyond the upright 11 and is provided with a driving pulley 29.

On the shaft 15, adjacent the upright 12, 15 is a wheel 30, equal in diameter to the diametrical distance between the bottom surfaces 23 of oppositely arranged half dies 21 on the member 17, while on the shaft 16 adjacent the upright 12, is a wheel 31, equal 20 in diameter to the diametrical distance between the bottom surfaces 23 of oppositely arranged half dies 21 on the member 26, this construction providing a space 32 between such wheels 30 and 31 through which the 25 broom bundles may be fed.

Mounted on any suitable support (not shown) are shafts 33 and 34 parallelly arranged with respect to each other and to the shafts 15 and 16. Pulleys 35 are rotatably 30 mounted on these shafts and carry a belt or carrier 36, of fabric, leather, or other suitable material provided near one edge with a plurality of equally spaced holes 38 which mesh with a plurality of equally 35 spaced radially projecting members 37 on the inner side of the member 17. The upper surface of the belt 36 is arranged in a horizontal plane adjacent to but slightly below the face 23 of the half dies 21 carried 40 by the member 17, as shown in Fig. 2. The members 37 meshing with the holes 38 in the belt 36 ensure a surface speed or travel of said belt equal to the surface speed or travel 45 of the circumference on which the face 23 of the half dies 21 is located. Attached to the belt 36 is a plurality of troughs 39, these troughs extending crosswise of the belt, the distance between troughs being equal to the circumferential distance between the half dies 21 on the members 17 50 and 26, and so arranged with relation to said half members as to be in alinement therewith as the half members 21 on the members 17 and 26, come into registry.

55 The broom bundles or units are comprised of a plurality of parallelly arranged fibres 40, having adjacent one end a cylindrical band 41 of sheet metal, this band being provided with diametrically arranged longitudinal grooves or depressions 42, which depressions assist in holding the fibres 40 in position when the band 41 is secured to the bundle.

60 The operation of my improved devices is as follows: The operator stands at the left

of the machine, as viewed in Fig. 2 and feeds bundles such as shown in Fig. 5 into the troughs 39 as the same move toward the members 17 and 26 in the direction of the arrow as shown in Fig. 2. The troughs 39 70 travelling at the same speed as the half dies 21 feed the bundles between said half dies which force the band 41 into a substantially oval shape and of the contour of the faces 22 and 23 of the half dies. The 75 grooves or depressions 42 in the band 41, give direction to the flow of metal as the bands pass through the half dies and the said grooves or depressions will be more pronounced after the above operation, this operation therefore forcing the grooves deeply into the bundles. During this operation, the bundles remain in the troughs 39 and are discharged therefrom into a suitable receptacle as they pass over the pulley. 80

85 While I have described the preferred embodiment of my invention somewhat in detail, it is to be understood that I may vary the size, shape, and arrangement of parts constituting my device within wide limits 90 without departing from the spirit of the invention. Further, while I have described and claimed the various novel combinations of elements as constituting a broom bundle making machine, it is of course obvious that 95 the use of my machine is not to be thus limited, and I may manufacture bundles for brooms, brushes and the like thereon.

99 My invention is further described and defined in the form of claims as follows:

1. In a machine of the character described, 100 the combination of a pair of positively driven wheels, a plurality of half dies, in the periphery of said wheels, the half dies in each wheel being adapted to successively register with each other during the rotation of the wheels and means for feeding broom bundles to said half dies.

2. In a machine of the character described, 110 the combination of a pair of positively driven wheels, means for rotating said wheels at equal circumferential speed, a plurality of half dies in the periphery of said wheels, the circumferential distance between half dies in each wheel being equal, said 115 half dies being adapted to register with each other as the wheels rotate, a belt provided with a plurality of parallelly arranged troughs, the distance between each trough being equal to the circumferential distance 120 between half dies on the wheels, and means for bringing each trough in succession into registry with the registering half dies on the wheels.

125 3. In a machine of the character described, the combination of a pair of positively driven wheels, means for rotating said wheels at equal circumferential speed, a plurality of half dies on the periphery of said 130 wheels, the circumferential distance between

half dies in each wheel being equal, said half dies being adapted to register with each other as the wheels rotate, a belt provided with a plurality of parallelly arranged 5 troughs, the distance between each trough being equal to the circumferential distance between half dies on the wheels, driving means on one of said wheels for moving the belt at the same speed as the circumferential 10 speed of said wheel, whereby each trough in succession is brought into registry with the registering half dies on the wheels.

4. In a machine of the character described, the combination of a pair of positively 15 driven wheels, mounted tangentially to each other and provided with interlocking positive driving means, a plurality of half dies in the periphery of said wheels, the half dies in each wheel being adapted to successively 20 register with each other during the rotation of the wheels, a bundle feeding belt, bundle holders on said belt, and means for positively driving said belt from one of said wheels at a surface speed equal to the cir-

cumferential speed of said wheel whereby 25 said bundle holders are brought successively into registry with the half dies.

5. In a machine of the character described, the combination of a pair of shafts, a pair of positively driven wheels, mounted tangentially to each other and provided with interlocking positive driving means, a plurality of half dies in the periphery of said wheels, the half dies in each wheel being adapted to successively register with each other during 30 the rotation of the wheels, a bundle feeding belt, bundle holders on said belt, and means for positively driving said belt from one of said wheels at a surface speed equal to the circumferential speed of said wheel, and a 35 wheel on each shaft spaced apart from the driving wheels and defining a passage through which the bundles are supported and fed.

In testimony whereof, I have signed my 40 name to this specification.

HARRY D. NEFF.
